UNITED STATES PATENT OFFICE

GUY CARPENTER, OF NEW YORK, N. Y.

SPARK ARRESTER

Application filed July 26, 1929. Serial No. 381,202.

My invention relates to that class of devices designed to prevent the escape of sparks, cinders, and the like, from the stack of a locomotive; and has for its object, to provide a device which will impart a helical motion to the products of combustion, whereby the cinders and other combustible materials in suspension are broken up into fine particles which, when they are small enough to be safe, are diverted by direction vanes so as to be passed through a screen. They will then be too small to carry sufficient fire to ignite any combustibles adjacent the railroad right of way.

My means for accomplishing the foregoing object may be more readily understood by reference to the accompanying drawings, in which—

Fig. 1 is a vertical sectional view through the smoke box of a locomotive;

Fig. 2 is a detail view of the direction vanes;

Fig. 3 is a view of the annular vanes for imparting a whirling motion to the products of combustion;

Fig. 4 is a vertical section through the front end of a locomotive, showing my improved mechanism installed in the smoke box;

Figs. 5 and 6 are detail views of the direction vanes;

Figs. 7, 8 and 9 are detail views of the annular vanes; and

Fig. 10 is a cross section of one of the annular vanes. Similar reference numerals refer to similar parts throughout the entire description.

As shown in the drawings, I provide a cylindrical intake chamber connecting the space around the base of the stack 1 with the front end of a locomotive. Only a fragmentary portion of the boiler tubes 3 is shown, as obviously the boiler of the locomotive forms no part of my invention. A smoke chamber 4 is formed in the smoke box 5, by partitions 6, 7 and 8. The lower partition 7 has an opening through which extends an exhaust nozzle 9 below the stack 1. The front wall partition 8 has an opening to which is fitted a cylinder 10, the front end of which is covered by a screen 11. The opening for the screen

11, however, is not concentric with the opening in the wall 8, but is concentric with the boiler shell 12 of the locomotive, so as to provide an annular space between the cylinder 10 and the boiler shell 12. In this annular space I mount a series of diagonally-inclined vanes 13, clearly seen in the detail views, Figs. 7 to 10. On the front end 14 of the locomotive I mount a series of curved direction vanes 15.

The operation of the invention is as follows:

The exhaust passing through the nozzle 9 creates a partial vacuum in the front end of the smoke box 5 of the locomotive, causing the products of combustion to pass through and out of the stack 1 at a high velocity. This high velocity is utilized to divert the products of combustion and cause them to travel circumferentially around the shell 12 of the boiler, by means of the diagonally-inclined vanes 13 located in the annular space intermediate the cylinder 10 and the boiler shell 12. Due to centrifugal forces which are produced by the high velocities, a rotary or helical motion of the gases is set up, and the cinders and sparks which are in suspension in the products of combustion are very effectually ground up and reduced to a size where they become harmless.

The centrifugal force, however, tends to retain the cinders, etc., in the front end of the locomotive, and I overcome this by means of the direction blades 15. These blades 15 tend to convert the movement of the solid particles, from a circular path in a plane normal to the axis of the boiler, to a path, or paths, still circular, but inclined to the axis of the boiler, thereby returning the particles to the screen 11, where the action of the flow of the gases will carry the particles through the screen 11, when they are pulverized small enough to pass through, thus effectively removing any danger of fire from escaping cinders. In other words, when the gases and cinders reach the forward end of the smoke box, there is a reversal in flow of the gases, and the cinders, which would otherwise be held by centrifugal force in a whirling mass at the periphery of the smoke

box, are caught by the direction vanes or blades 15, and together with the gases, are given a vertical motion by these blades, in a rearward direction. The blades 15 are adjacent the point of highest draft, and therefore the cinders and gases flowing from them to the stack travel in a diminishing spiral or vortex towards the point of discharge.

Although I have shown and described my invention as equipment for a locomotive, it will be obvious, to persons skilled in the art, that the principle involved in the invention is capable of being utilized for removing dust or air from gas, or for the proper mixing 10 of air or dust with gas, as in the case of the burning of pulverized or powdered fuel; and while the drawings show a concrete embodiment of my invention, I do not desire to be understood as limiting myself to this specific embodiment, as it represents only one preferred form of my invention, and I therefore reserve to myself such changes as may fall within the scope of the hereinafter appended claims.

Having described my invention, what I regard as new, and desire to secure by Letters Patent of the United States, is:

1. The combination, with a locomotive having boiler tubes and a shell, of a smoke box 30 at the forward end of said boiler tubes, a stack which leads from said smoke box, partitions which form a chamber which encloses the lower end of said stack, an exhaust nozzle which leads into said chamber below said stack, an exhaust port in the front wall of said chamber, a cylindrical member connected to the front wall of said chamber, which surrounds said port, there being an annular space between the outer wall of 40 said cylindrical member and the shell of the boiler, a plurality of diagonally-inclined vanes located in said annular space, a series of curved direction blades attached to the front end of the smoke box, and a screen covering the opening to the cylindrical member.

2. The combination, with a locomotive having boiler tubes and a shell, of a smoke box at the forward end of said boiler tubes, a stack which leads from said smoke box, partitions which form a chamber which encloses the lower end of said stack, an exhaust nozzle which leads into said chamber below said stack, an exhaust port in the front wall of said chamber, a cylindrical member, connected to the front wall of said chamber, which eccentrically surrounds said port, there being an annular space between the outer wall of said cylindrical member and the shell of the boiler, a plurality of diagonally-inclined vanes located in said annular space, a series of curved direction blades attached to the front end of the smoke box, and a screen covering the opening to the cylindrical member.

3. The combination, with a locomotive hav-

ing boiler tubes and a shell, of a smoke box at the forward end of said boiler tubes, a stack which leads from said smoke box, partitions which form a chamber which encloses the lower end of said stack, an exhaust nozzle 70 which leads into said chamber below said stack, an exhaust port in the front wall of said chamber, a cylindrical member connected to the front wall of said chamber, said cylindrical member being mounted concentric to the shell of the boiler, there being an annular space between the outer wall of said cylindrical member and the shell of the boiler, a plurality of diagonally-inclined vanes 75 located in said annular space, a series of curved direction blades attached to the front end of the smoke box, and a screen covering the opening to the cylindrical member.

4. The combination, with a locomotive having boiler tubes and a shell, of a smoke box at the forward end of said boiler tubes, a stack which leads from said smoke box, partitions which form a chamber which encloses the lower end of said stack, an exhaust nozzle which leads into said chamber below 80 said stack, an exhaust port in the front wall of said chamber, a cylindrical member connected to the front wall of said chamber, which surrounds said member, said member being eccentric to the said port but concentric to the shell of the boiler, there being an annular space between the outer wall of said cylindrical member and the shell of the boiler, means located in said annular space 85 directing the products of combustion into a circular path, means attached to the front end of the smoke box to divert said products of combustion into the cylindrical member, and a screen covering the opening to the cylindrical member.
